UNITED STATES PATENT OFFICE.

RICHARD F. ROEHL, OF CHICAGO, ILLINOIS, ASSIGNOR, BY MESNE ASSIGNMENTS, TO
ILLINOIS MOTOR COMPANY, OF CHICAGO, ILLINOIS, A CORPORATION OF ILLINOIS.

INTERNAL-COMBUSTION ENGINE.

1,321,128.

Specification of Letters Patent. Patented Nov. 11, 1919.

Application filed April 7, 1917. Serial No. 160,367.

To all whom it may concern:

Be it known that I, RICHARD F. ROEHL, residing in Chicago, in the county of Cook and State of Illinois, have invented certain new and useful Improvements in Internal-Combustion Engines, of which the following is a specification.

My invention has reference to an improved two cycle internal combustion engine, the same being especially designed for use as a motor cycle engine and having as one of its principal objects to improve the construction and increase the efficiency and utility of engines of this type. Another object of the invention is to provide an engine in which excessive speeds are attained and maintained with perfect quietness of action, and without liability of miss-fire or base explosion. A still further object is the provision of a novel construction of manifold and piston controlled by-pass operating to create pressure in the manifold in the downstroke of the piston and thereby aid in unseating the valve in the end inlet-port of the cylinder.

My invention also contemplates certain novel details of construction, combination and arrangement of parts of the improved engine, whereby certain advantages are attained, as will be more fully described hereinafter, and pointed out in the claims.

These, together with such other objects as may hereinafter appear, or are incident to my invention, I attain by means of a construction illustrated in preferred form in the accompanying drawings, wherein:—

Figure 1 represents a central vertical longitudinal section of my improved engine;

Fig. 2 is a view of the engine in perspective, the manifold being dissociated from the cylinder proper;

Figs. 3 and 4 are front and rear views of the manifold;

Fig. 5 represents a view in perspective of a fragmentary portion of the cylinder and illustrating the ports leading to the port chamber; and

Fig. 6 is a view in perspective of the ported piston.

Referring to the drawings, the reference numeral 7 designates the cylinder which is formed with radiating fins 8, and provided with a suitable igniting device 9 carried in the head 10 of the cylinder. Associated with the lower portion 7^a of the cylinder 7

is a crank-case 11 provided with a fly-wheel 12 and crank shaft 13, the latter being connected by a piston rod 14 with a piston 15 adapted for reciprocative movement in the cylinder. Above and below the piston head 16 are the working and compression chambers 16 and 17, respectively.

At the upper end of the working chamber 16 is an end outlet port 18 controlled by a back check valve 19, and at the lower end 65 of the same is a series of exhaust ports 20 and a series of oppositely disposed open side inlet ports 21, the exhaust ports being so located and formed as to exhaust in the downstroke of the piston prior to or simultaneously with the admission of gas through the side inlet ports past the deflecting portion 22 of the piston head 15^a into the working chamber.

Formed in the side wall of the lower cylinder portion 7^a is a series of ports 23 disposed in vertical alinement with and below the series of side inlet ports 21, but spaced apart therefrom by the intervening web portion 7^b of the cylinder, (see Fig. 1). The 75 wall of the cylinder is also extended outwardly to constitute a port chamber 24 or casing for the ports 21 and 23, there being a connecting passage 25 or by-pass between the said ports and a single opening 26 whose 80 mouth at the upper end of the passage 25 is in substantial alinement with the ends of the fins 8 in one direction and with the ports 21 in the other direction, the lower end of the passage being closed.

About the openings 18 and 26 are flanges 27, 28, provided with stud screws 27^a and 28^a, respectively, adapted to pass through openings formed in the corresponding flanges 29, 30, of the manifold 31, and by 95 means of nuts co-operating with said screws the manifold is designed to be secured in position against the cylinder, and straddling the fins, as in the manner shown in Fig. 1.

This manifold has a centrally enlarged portion 32 formed in its outer face with a charge intake opening 33 threaded to receive the valve casing 33 of the back check valve 34, which latter is designed to control the inflow of gas from any suitable carburetor or other charge forming device, and to prevent the new charge from being forced back into the carburetor upon the downstroke of the piston. Both valves 19 110

and 34 have guided stems 19^a and 34^a, and are held seated by light tension springs 19^b, 34^b, engaging caps 19^c, 34^c, respectively, said caps adjustable on their respective stems to vary the tension of the springs, as will be readily understood.

This enlarged portion 32 of the manifold has within it a chamber 35, and extending vertically in opposite directions therefrom are relatively narrower ducts, the upper of which, indicated by the numeral 36, communicates laterally with the end inlet-port 19, and the lower duct 38 in turn communicates laterally with the opening 26 in the port casing 24. The upper duct, as will be seen, carries the back check valve 19, and terminates in the flange 29 which is chamfered inwardly to form a seat 39 for this valve, the end inlet port 18 being slightly larger in diameter than the valve and the lateral portion of the duct 36 through which the valve stem 19^a extends in a guided relation. An advantageous feature of this manifold resides in the fact that it is detachable and carries all the valves which are easily accessible when the manifold is detached.

With a view of controlling the serially arranged ports 21 and 23 in the movement of the piston, the latter has a solid upper portion 40, provided with piston rings 41, designed when the crank shaft 13 is at bottom center to register with the web portion 7^b (Fig. 1), and below it the piston wall is formed with two rows of superposed ports 42 and 43 adapted to register with the above mentioned ports during piston movement, whereby to unseat the intake valve during the upstroke and to coöperate with the suction created in the working chamber 16 during the downstroke of the piston by creating pressure in the manifold chamber 35 back of the end inlet valve 19 to aid in the unseating of the valve. Preferably, the distance between the top line of the ports 21 and the bottom line of the ports 23 is similar to that between the top and bottom lines of the ports 42 and 43, the latter, though, having a vertical length somewhat greater than that of the ports 21 and 23.

With the parts positioned as shown and described, the operation is as follows:—On the upstroke, the end inlet valve 19 closes and the intake valve opens, the suction created in the compression chamber opening the intake valve 34 and causing a flow of gas through passages 38 and 25 into said chamber as the piston rises, the piston ports 42 and 43 being in register with one or the other of the series of ports 21 and 23, and with both midway of the stroke, until the lip 44 of the piston is in register with the side inlet ports 21, and the charge in the working chamber is under full compression for its ignition by the spark plug 9. During the

downstroke, the ports similarly register, and the charge in the compression chamber under compression passes upwardly into the chamber 35 to effectively create a pressure against the back of the valve 19. As soon as the exhaust ports 20 uncover, and the pressure in the working chamber 16 is less than that existing in the chamber 35, the valve 19 opens and the new charge rushes through the end inlet-port 18 into the compression space 45 of the working chamber, and impacting against the inclined head wall 10 of the cylinder the charge passes down to expel the exhaust charge through the exhaust ports. Further movement of the piston to uncover the port 21 will permit the balance of the compressed new charge to pass into the working chamber after the compression therein has been lowered below the force of the spring 19^b, which closes the valve 19 and hence the port 18. On the upstroke of the piston, the new charge is compressed and ignited as before to impel the piston on its working stroke, thus completing the cycle of operation.

From the foregoing description, taken in connection with the accompanying drawings, it is thought that the completed construction, operation, and advantages, together with the simplicity of my invention, will be readily understood by those skilled in the art.

What I claim is:—

1. In a motorcycle engine of the two-cycle crank compression type, the combination of a cylinder having working and compression chambers and provided with an outwardly directed gas port, a piston in said cylinder, said working chamber having an end inlet port, a valve for holding said end inlet port closed substantially throughout the downstroke of the piston, said compression chamber formed with a passage providing an avenue of communication between said compression chamber and said gas port substantially throughout piston movement, a gas conducting manifold having an enlarged valved intake chamber provided at each side thereof with branch ducts of relatively smaller diameter associated with the end inlet port and said outwardly directed gas port.

2. In a motorcycle engine of the two-cycle crank compression type, the combination of a cylinder having working and compression chambers and provided with an end inlet port and a side inlet port, said compression chamber provided with an outwardly projecting gas chamber and a series of inner gas conducting ports and an outer gas conducting port providing communication between the working and compression chambers, a hollow piston in said cylinder formed serially with ports adapted to register with said side port and said inner gas conducting ports, a gas conducting manifold having

- a central enlarged chamber formed with a valved intake opening, and provided terminally with branch ducts of relatively smaller diameter detachably connected with the outer port of said gas chamber and said end inlet port, and a valve for the end inlet port having a lesser diameter than the valve for the intake opening.
3. In an internal combustion engine, the combination of a cylinder having a working chamber provided with an end inlet port, a compression chamber in the lower part thereof provided with an outwardly projecting gas chamber having inner and outer ports, a piston in said cylinder, a valve for said inlet port provided with a spring for holding it closed, substantially throughout the downstroke of the piston, a charge conducting manifold connecting the outer port of the gas chamber with said inlet port to form a walled passage therebetween and provided with an enlarged intake chamber, and a spring-held intake valve movable in said intake chamber and having a diameter greater than the diameter of said passage, said piston ported near the head of the compression chamber to communicate with the intake of the manifold through the ports of the gas chamber substantially throughout the upstroke of the piston, and said gas chamber and manifold constituting an extension of the compression chamber for conducting gas during the greater part of the piston movement.
4. In a motor-cycle engine of the two-cycle crank compression type, the combination of a cylinder having a working chamber provided in its head with an end inlet port, a compression chamber in the lower part thereof provided with a gas chamber having inner and outer ports, a piston in said cylinder at the head of the compression chamber, a valve for said inlet port provided with means for yieldingly holding it closed substantially throughout the downstroke of the piston, a charge conducting manifold provided with a seat for said valve and detachably connecting the outer port of the gas chamber with said inlet port to form a walled passage therebetween, said manifold provided in the wall of said passage above said outer port with an intake having a diameter greater than that of the said outer port, a valve seated in said intake and opening into said passage near said inlet port and forming part of the wall of said passage, said piston ported to communicate with the intake of the manifold through the ports of said gas chamber and said passage substantially throughout the upstroke of the piston.
5. An internal combustion engine cylinder having, in combination, a working chamber provided with an end inlet port, a piston in said cylinder, a charge conducting manifold associated at one end with said port and provided with an intake valve, and a compression chamber having an outer gas chamber, the latter being provided with a passage communicating with the other end of the manifold, said passage serving as a gas conductor substantially throughout the cycle of piston movement and having a cross-sectional area less than that of either the intake valve or said outer gas chamber.
6. An internal combustion engine cylinder having, in combination, a working chamber provided with an end inlet port, a piston in said cylinder, a compression chamber having an outer gas chamber provided with an outer gas port, a valve for holding said inlet port closed substantially throughout the downstroke of the piston, and a charge conducting manifold detachably connected at its ends with said inlet port and said outer gas port and provided intermediately thereof with an intake chamber and an intake valve therefor, the cross-sectional area of said outer gas port being less than that of either of the intake valve or said outer gas chamber, and both of said valves being carried by said manifold and detachable therewith.
7. An internal combustion engine cylinder having in combination, working and compression chambers and provided with an outer gas port, a piston in said cylinder, said working chamber having an end inlet port and said compression chamber provided with an enlarged chambered passage leading therefrom to said outer gas port, an intake manifold having an intake chamber and a gas intake port therefor and provided with a valve for the end inlet port and a valve for the intake port, said passage communicating with the intake chamber through said gas port in the downstroke and upstroke of the piston and said gas port having a cross-sectional area less than that of the said chambered passage.
8. An internal combustion engine cylinder having, in combination, a working chamber provided with a valved inlet port, a piston in said cylinder, a compression chamber, an outer gas chamber, the wall of the cylinder ported to permit communication between the outer gas chamber and the compression chamber substantially throughout the cycle of piston movement, a manifold having a gas intake chamber and an intake valve therefor, said manifold positioned between the outer gas chamber and said inlet port and constituting with said outer gas chamber a chambered gas induction and storage passage during such piston movement, a part of said passage between the outer gas chamber and the intake valve being constructed to act as a suction zone for said valve.
9. An internal combustion engine having,

in combination, a working chamber provided with an end inlet port, a piston in said cylinder, a compression chamber, an outer gas chamber, a manifold connected with said inlet port having an intake port and a gas intake chamber adapted to communicate through the lower end of said manifold with said outer gas chamber, a valve in said intake chamber for said intake port, the confronting wall portions of said outer gas chamber and piston being ported

to provide unobstructed communication between the manifold and the compression chamber substantially throughout the cycle of piston movement, and a valve at the upper end of the manifold holding said inlet port closed substantially throughout the downstroke of the piston. ¹⁵

In testimony whereof I have hereunto signed my name to this specification.

RICHARD F. ROEHL.
